Patented Apr. 18, 1922.

2 SHEETS—SHEET 2.

UNITED STATES PATENT OFFICE.

DANIEL WESLEY KEITH, OF KEITHVILLE, LOUISIANA.

PUMP.

1,413,165.

Specification of Letters Patent. Patented Apr. 18, 1922.

Application filed August 9, 1920. Serial No. 402,114.

To all whom it may concern:

Be it known that I, DANIEL W. KEITH, a citizen of the United States, residing at Keithville, in the parish of Caddo and State 5 of Louisiana, have invented certain new and useful Improvements in Pumps, of which the following is a specification.

This invention relates to improvements in pumps especially adapted for use in connection with wells and cisterns.

An important object of this invention is to provide a well pump having a plurality of pumping cylinders which may be alternately brought into communication with the 15 discharge pipe or conduit by means of a single pivoted valve.

A further object of this invention is to provide a well pump having means whereby the water within the discharge pipe may be returned to the well at the completion 20 of the pumping operation so that the water will be kept cool.

A further object of the invention is to provide a pump of the class described which 25 is of highly simplified construction, reliable in use and cheap to install.

Other objects and advantages of the invention will be apparent during the course of the following description.

30 In the accompanying drawing forming a part of this application and in which like numerals are employed to designate like parts throughout the same,

Figure 1 is an elevation of the improved 35 pump,

Figure 2 is a detail sectional view through the same, the view illustrating the valve arrangement,

Figure 3 is a side elevation of a slightly 40 modified form of invention,

Figure 4 is a detail sectional view of the pump having a slightly modified valve arrangement.

In the drawing wherein for the purpose 45 of illustration is shown a preferred embodiment of the invention, the numeral 10 generally designates the improved pump comprising cylinders 12 and 14, arranged in spaced parallel relation and preferably 50 embedded in the ground so that the openings 16 and 18 respectively in the lower ends of the same are disposed below the water level, whereby the water may be drawn into the cylinders.

55 Pistons 20 and 22 are slidably mounted within the cylinders 12 and 14 respectively

and have piston rods 24 connected to a crank shaft 26 by means of links 28. In the form of the invention illustrated in Figure 1, the crank shaft 26 is rotatably supported upon 60 the bearings 30 carried by the standards 31 of a platform designated by the numeral 32. The crank shaft is provided with an operating crank 34 which is adapted to be manually rotated. A wheel 33 may be 65 mounted upon one end of the crank shaft so that the crank shaft may be rotated by a suitable source of motive power. During the upward movement of the piston 20, a quantity of water is drawn from the well or 70 cistern through the opening 16 into the cylinder 12. A flap valve 38 is horizontally pivoted in the lower portion of the chamber as indicated at 39 and during a subsequent 75 downward movement of the piston closes the opening 16 and thereby prevents the return of the water to the well or cistern. During the downward movement of the piston, the water is forced through a lateral opening 40 in the cylinder wall 12 and 80 through a passage 41 in a valve casing 42. As the water is forced through the passage 41 in the valve casing 42, the same enters a V-shaped chamber 44 within which a V-shaped valve 45 is horizontally pivoted as 85 indicated at 46. The passage of water through the channel 41 of course moves the valve 45 to the left and thereby allows the water to pass through the V-shaped chamber 44 into a discharge pipe or conduit 47.

90 During the downward movement of the piston 20, the piston 22 is of course partaking of an upward movement thereby drawing water from the well to the cylinder 14 through the opening 18. As the water is 95 drawn into the cylinder 14, a horizontally pivoted or hinged flap valve 48 is elevated so as to uncover the opening 18. On the subsequent downward movement of the piston 22 the water is forced downwardly and the 100 flap valve 48 closes the opening 18 so that the water is directed through an opening 50 in the side wall of the cylinder 14 and then through a passage 51 in the valve casing 42. The passage of the water through the passage 51 moves the horizontally pivoted valve 45 to the right and thereby establishes 105 communication between the passage 51 and the chamber 44. The passages 41 and 51 are inclined upwardly in the direction of the 110 discharge conduit 47 so that the water may freely enter the conduit upon leaving the

casing 42. This movement of the horizontally pivoted valve 45 closes the passage 41 so that as the piston moves upwardly in the cylinder 12, the water will not be allowed 5 to flow back through the passage 41.

The pipe 47 may extend to a suitable point 10 of discharge or may have a spout 54 at a point above the ground.

As illustrated in Figure 1, the discharge 15 pipe 47 is provided with a drain pipe 55 which extends back into the cistern or well so that when the pumping operation is completed the water within the pipe 47 will return to the well and thereby be kept cool.

15 In the form of the invention illustrated in Figure 3, the upper ends of the links 28 are pivoted to a lever 60 having one end portion formed with a handle 61 adapted to be moved vertically so as to impart a corresponding movement to the piston rods 24. 20 In this form of the invention, the discharge conduit 47 has its upper end formed with apertured ears 62 between which the intermediate portion of the lever 61 is horizontally pivoted by means of a pin 64. The form of operating means illustrated in Figure 3, allows the operator to draw a constant and uniform stream of water through the discharge conduit 47. The conduit 47 may, 25 in both forms of the invention, be provided with a bracket 65 having vertically arranged sleeves 66 which slidably receive and guide the vertically movable piston rods 24.

With reference to Figure 4, it will be observed that flap valves 38 and 48 may be displaced by spherical valves 68 adapted to seat on the upper walls of the openings 16 and 18 so that the same will be elevated upon the passage of water through the openings. 40 The spherical valves may be provided with stems 70 having their lower portions provided with retaining disks 71 which serve to limit the upward movement of the spherical valves.

45 The lower portions of the cylinders 12 and 14 may be supported in spaced relation to the bottom of the well by means of a plurality of vertically arranged standards 74 mounted upon a flat base 75.

50 With reference to the foregoing description taken in connection with the accompanying drawings, it will be observed that a pump constructed in accordance with this invention may be conveniently operated with

55 a minimum of effort on the part of the

operator. Further, it will be observed that the valve arrangement allows of free discharge of water from the well and that the valves will not be rendered inoperative as the result of continued use or abuse. 60

Having thus described the invention, what is claimed as new is:

1. A pump comprising spaced cylinders having openings in their lower ends, valves for said openings, a valve casing interposed between the cylinders and integral therewith and provided with a V-shaped chamber opening through the top of said casing, there being oppositely disposed downwardly inclined passages formed in the casing and 65 communicating with the chamber and cylinders respectively, an oscillating valve pivoted at its lower end within the chamber and adapted to alternately close the passages, pistons operating within the cylinders 70 above the valves, a discharge pipe arranged between the cylinders and having its lower end provided with a laterally extending flange detachably secured to the casing and bearing against the exterior walls of the 75 cylinders, said discharge pipe forming a closure for the upper end of the chamber and being provided with a downwardly directed drain discharging in the direction of said flange. 80

2. A pump comprising spaced cylinders open at both ends and connected by a transverse valve casing integral with the cylinders, a base including spaced plates connected by standards, one of said plates forming a support for the pump and the other plate constituting the bottom of the cylinders and having valve openings therein, valves disposed at said openings, there being a V-shaped valve chamber formed in the 90 casing and opening through the top thereof, and oppositely disposed downwardly inclined passages communicating with the valve chamber and the interior of the cylinders, an oscillating valve having its lower 95 end pivotally mounted within the V-shaped chamber, pistons operating within the cylinders, a discharge pipe forming a closure for the valve chamber and having its lower end provided with a laterally extending flange 100 detachably secured to the valve casing, and a drain pipe communicating with the discharge pipe near the lower end thereof. 105

In testimony whereof I affix my signature.

DANIEL WESLEY KEITH. [L.S.]
